(57) CLAIM

We claim the ornamental design for a firearm handguard, as shown and described.

DESCRIPTION

FIG. 1 is a top perspective view of the new design of a firearm handguard, according to a first embodiment;

FIG. 2 is a front view of the new design of the firearm handguard, according to the first embodiment;

FIG. 3 is a first side view of the new design of the firearm hand guard, according to the first embodiment;

FIG. 4 is a rear view of the new design of the firearm handguard, according to the first embodiment;

FIG. 5 is a top view of the new design of the firearm handguard, according to the first embodiment;

FIG. 6 is a second side view of the new design of the firearm hand guard, according to the first embodiment;
FIG. 7 is a bottom view of the new design of the firearm handguard, according to the first embodiment;
FIG. 8 is a top perspective view of the upper half of the new design of a firearm handguard, according to the first embodiment;
FIG. 9 is a top perspective view of the new design of a firearm handguard, according to a second embodiment;
FIG. 10 is a front view of the new design of the firearm handguard, according to the second embodiment;
FIG. 11 is a first side view of the new design of the firearm handguard, according to the second embodiment;
FIG. 12 is a rear view of the new design of the firearm handguard, according to the second embodiment;
FIG. 13 is a top view of the new design of the firearm handguard, according to the second embodiment;
FIG. 14 is a second side view of the new design of the firearm handguard, according to the second embodiment;
FIG. 15 is a bottom view of the new design of the firearm handguard, according to the second embodiment; and,
FIG. 16 is a top perspective view of the upper half of the new design of the firearm handguard, according to the second embodiment.

Portions of the article illustrated in broken lines are unclaimed subject matter forming no part of the claimed design.
